BATTERY TERMINAL CONNECTOR

Abraham Tisman, Bronx, N. Y.

Application September 14, 1944, Serial No. 554,052

2 Claims. (Cl. 173—259)

1

This invention relates to connectors or couplings used in coupling circuit wires or cables with electrical terminals. More particularly, the invention deals with connectors of this kind adapted for use on the terminals of storage batteries as commonly used on various types of vehicles and apparatus and, particularly, automobiles. Still more particularly, the invention deals with connectors having means for spreading or expanding the same to free the connectors from the terminals facilitating quick uncoupling of the connectors and, further, the invention deals with connectors of this kind having means for pulling the connectors from the terminals.

The novel features of the invention will be best understood from the following description, when taken together with the accompanying drawing, in which certain embodiments of the invention are disclosed and in which the separate parts are designated by suitable reference characters in each of the views and in which:

Fig. 1 is a side view of a connector illustrated as arranged upon the terminal of a battery with part of the construction broken away and in section.

Fig. 2 is a plan view of the structure shown in Fig. 1 illustrating the spreading of the connector in dot and dash lines; and

Fig. 3 is a side view showing a modified form of connector which I employ.

This application constitutes a continuation in part of my prior application Serial Number 552,079, filed August 31, 1944.

In various types of electrical terminals to which connectors or couplings are attached, often times difficulty is experienced in freeing or detaching the connector or coupling from the terminal. This is particularly true in connection with battery terminals, especially as used upon motor vehicles.

With my improved connector or coupling construction, I provide means for spreading a split connector or coupling after the clamping bolt has been loosened in order to free the connector or coupling from the terminal to which it has been attached. Still further, when connectors or couplings of this kind have become frozen upon the terminals, means is also provided to pull the connector or coupling from the terminal after the same has been spread in the manner previously described. While my invention is adaptable for use in connection with more or less standard types of couplings, that is to say, couplings which do not employ the pulling attachment, in the present illustrations of the in-

2

vention the same has been applied to devices incorporating the pulling attachment, the devices showing two different types and kinds of attachments for the conductor cable.

In Fig. 1 of the drawing, I have shown at 10 the upper portion of a part of a storage battery and at 11 is indicated one of the terminals of the battery in the form of an outwardly tapered plug. At 12, in Figs. 1 and 2 is shown one form of connector which I employ.

The connector 12 comprises a split sleeve portion 13 adapted to be fitted around the terminal 11 and having a pair of projecting wings 14; note Fig. 2 of the drawing, through which is passed a bolt 15 for clamping the sleeve portion 13 firmly upon the terminal 11.

On the sleeve portion, opposite the projecting wings 14, is a radial projection 16 terminating in a U-shaped cable coupling 17; the channel 18 of which is directed upwardly. The channel opens through one end of the coupling 17 and the other end 19 is closed and adapted to receive a clamp bolt 20. The terminal end of a cable or conductor is indicated at 21. This end is arranged in the channel 18 and held therein by a clamp block 22 fitting in the channel 18 and held in clamping position by the bolt 20.

Extending upwardly from the projection 16, inwardly of the coupling 17, is an L-shaped bracket 23. The end 24 of this bracket is arranged in spaced relation to and directly above the sleeve 13 and has a threaded bore 25 in axial alignment with said sleeve. In the bore 25 is arranged a pull screw 26 having a suitable head 27 for rotating the same and this screw carries at its inner end a cup-shaped bearing member 28 which is adapted to bear upon the upper end of the terminal 11, so that when the sleeve 13 is loosened around the terminal 11, the rotation of the screw 26 moves the member 28 downwardly.

The connector 12 will be drawn or pulled upwardly and freed from the terminal 11. The screw 26 has a rotatable mounting 29 in the member 28, so as to prevent rotation of the member on the terminal in the operation of pulling the connector.

With the present construction, the arms 14 include outward extensions 30, one of which is preferably provided with a cut-away inner surface 31 and the other of which is provided with an outwardly extending enlarged portion 32, providing a long bearing for a spreader screw 33, which is in threaded engagement with the last mentioned arm, including its enlargement 32, a suitable head 34 being provided for the rotation

of the screw. The screw 33 bears upon the inner surface 31 to spread the arms 14 when the bolt 15 is loosened. This operation will in most instances expand the bore of the sleeve 13 sufficiently to free the sleeve from the terminal 11, thus providing free removal of the connector. However, in some instances, where the connector becomes frozen upon part of the wall structure of the terminal, it may be necessary to pull the connector from the terminal and, in such instances, the pull screw 23 is operated.

The cut-away portion, as at 31, is provided primarily to provide full and complete clamping of the sleeve 13 upon the terminal 11, in other words, in maintaining as great a clearance between adjacent surfaces of the extensions 30 as provided between adjacent surfaces of the arms 14.

In Fig. 3 of the drawing is shown a slight modification, wherein the connector 35 has a sleeve portion 36 similar to the sleeve 13, projecting arms 37, similar to the arms 14 coupled together by a bolt 38; extensions 39 on the arms similar to the extensions 30 and a spreader screw 40 similar to the screw 33.

The connector 35, instead of having the coupling as at 17, is provided with a radially extending tubular socket portion 41 for receiving a conductor or cable end 42, the latter being held in the socket by a set screw 43, as in other devices of this kind.

Extending upwardly from the socket 41 is a bracket 44 having a reinforcing rib, as indicated at 45 and a projection 46 arranged axially above the sleeve 36.

In the projection 46 of the bracket is arranged a pull screw 47 similar to the screw 26 and having a bearing cup 48 similar to the cup 28. Aside from the different form of bracket employed, the structure of Fig. 3 differs primarily from the structure, shown in Figs. 1 and 2 in the provision of the radial socket 41 for mounting the conductor or cable. The coupling 71, as will clearly appear in Fig. 2 of the drawing, adapts the connector for arrangement to the conductor at a position at right angles to the radial line or at what might be termed a tangent to the sleeve of the connector.

As previously stated, in many uses and, particularly, where the connectors are frequently coupled and uncoupled with respect to the terminals, the use of the pulling attachment is not required. In such instances, this attachment will not be employed on the connector and the spreader attachment alone will be provided.

Having fully described my invention, what I claim as new and desire to secure by Letters Patent is:

1. A terminal connector of the class described, said connector comprising a split sleeve having a pair of projecting arms at the split portion of the sleeve and arranged in spaced relationship to each other, means engaging the arms of said sleeve for clamping the sleeve on a terminal, and a screw in threaded engagement with one of said arms and having a bearing upon the inner surface of other of said arms for spreading said arms in freeing the sleeve from a terminal when the last means is loosened.
- 15 2. A terminal connector of the class described, said connector comprising a split sleeve having a pair of projecting arms at the split portion of the sleeve and arranged in spaced relationship to each other, means engaging the arms of said sleeve for clamping the sleeve on a terminal, said arms having extensions, one extension having an enlarged portion, a screw in threaded engagement with said enlarged portion of said extension, the other of said extensions having a cut-away inner bearing surface spacing the extensions of said arms a greater distance apart than the spacing between adjacent surfaces of said arms, and said screw being adapted to engage the bearing surface of the second named extension in spreading the arms to free said sleeve from a terminal engaged thereby.
